UNITED STATES PATENT OFFICE.

ALBERT L. CHALFONTE, OF TRENTON, NEW JERSEY, ASSIGNOR TO MERGENTHALER LINOTYPE COMPANY, A CORPORATION OF NEW YORK.

SLUG-CASTING MACHINE.

Application filed September 5, 1925. Serial No. 54,652.

My invention relates to slug casting machines, such as linotype machines of the general organization represented in Letters Patent of the United States, No. 436,532, to O.

- 5 Mergenthaler, wherein circulating matrices are released from a magazine in the order in which their characters are to appear in print and then assembled in line, the composed line transferred to the face of a mold, the mold 10 filled with molten metal to form a slug or linotype against the matrices which produce the type characters thereon, and the matrices thereafter returned through distributing mechanism to the magazine from which they 15 started.

In these machines it is customary to mount the molds on a rotatable wheel or disc, whereby the mold selected for use is first presented in the slug casting position 20 and then carried around to the slug ejecting position, at each cycle of operation of the machine. Before the slug is cast, the active mold is pressed tightly against the composed line of matrices at the front, and the mouth-piece of the type metal pot is likewise 25 pressed tightly against the mold at the rear. The molten metal is then forced under pressure into the mold slot and up against the intaglio characters of the matrices to form 30 the slug or linotype. In practice, it has been found that unless the contact of the rear face of the mold with the mouthpiece of the melting pot is substantially perfect at all times, thin films or fins of metal will accumulate 35 on the rear face of the mold and impair the "lock-up" to such extent that "back squirts" and other serious difficulties are likely to result.

The present invention contemplates an improved mold wiper, which is intended to obviate these difficulties by removing, after 40 each casting operation, any metal that may adhere to the back of the mold. In the embodiment illustrated, there is employed a wiping pad resiliently mounted on a normally fixed support, which is adjustably secured to a rigid bracket fastened to the machine frame.

In the accompanying drawings I have 45 shown my invention only in preferred form and by way of example, but obviously many changes and variations may be made therein and in its mode of operation that will still be comprised within its spirit. Generally 50 speaking, I desire it to be understood that

I do not limit myself to any specific form or embodiment except in so far as such limitations are set forth in the appended claims.

In the accompanying drawings:

Fig. 1 is a fragmentary sectional perspective view of a portion of a linotype machine, showing my invention applied thereto;

Fig. 2 is a vertical section view on an enlarged scale of the improved mold wiper;

Fig. 3 is a detail section, showing a modification.

As shown in Fig. 1, the mold wheel or disc A is of ordinary construction and equipped with a plurality of molds A¹, any one of 70 which may be selected for use as desired. An intermittently driven pinion B, arranged in mesh with the toothed flange of the disc, rotates the latter in an anti-clockwise direction first to present the active mold in casting 75 position, and thereafter to carry it around to ejecting position, at each cycle of operation. Before casting, the disc A is advanced to press the front face of the active mold A¹ (which then occupies a horizontal position) 80 firmly against the composed line of matrices X, which are clamped tightly between vise jaws C to prevent leakage of metal through the line at the time of casting. At about the same time, the melting pot D¹ is swung forwardly to press its mouthpiece D tightly against the back of the mold. In this "lock-up" condition of the parts, molten metal is 85 forced from the pot D¹ through the mouthpiece D into the mold slot A² and up against 90 the composed line of matrices X at its front for the casting of the slug. The parts just described and their mode of operation are well-known in the art and constitute no part 95 of my invention.

As before stated, the present invention is directed to an improved wiping device which will serve to keep the rear face of the slug-casting mold in a clean and smooth condition and free from adhering particles of type 100 metal. In the embodiment illustrated, the improved device comprises a wiping pad E (which may be of felt or other suitable material) mounted in a support F and arranged in the path of the molds so that the active 105 one, in passing from the casting to the ejecting position, will brush across the exposed face of the pad and thus be cleansed or freed of any metal or other foreign matter adhering to the rear face thereof.

The support F, while normally occupying a fixed position, is mounted so as to be adjustable at will to and from the rear face of the disc A in order to compensate for wear of the pad E and to better adapt the device to outstanding machines, it being understood that the position of the mold disc relatively to other parts of the machine is likely to vary in different models. As shown in Fig. 2, the support F comprises a cylindrical recessed end portion or casing F¹ and a shank portion or stem F², the latter being adjustably secured by a clamp screw F³ in the upper end of a bracket G fastened by a screw bolt G¹ to the base frame of the machine. Preferably, the recessed portion F¹ and the shank portion F² are separately produced and screwed together as at F⁴, the former being made of cast metal and the latter of rolled steel.

The pad E is properly sized to fit snugly within the recess F⁵ of the end portion F¹ and is resiliently supported therein by means of a short compression spring H located in said recess F⁵ and pressing forwardly against a reinforcing plate E¹ fastened to the rear face of the pad. These parts (see Fig. 2) are maintained in proper assembled relation by a shouldered screw J tapped into the threaded end of the stem F² and formed with an elongated shank J¹ and a head J². The pad E is apertured at E² to accommodate the head of said screw so that it may bear against the reinforcing plate E¹ and thus limit the forward movement of the pad under the pressure of the spring H, the shank J¹ of the screw being long enough to allow the front face of the pad to protrude a little distance beyond the end of the support F.

According to the foregoing arrangement, and after the original setting of the bracket G to bring the support F in proper angular relation to the rear face of the mold disc A, the support F is shifted in the bracket toward the disc until the pad E, by its engagement with the latter, places the spring H under the desired tension. The clamp screw F³ is then tightened to secure the support to the bracket G, thus maintaining the pad resiliently engaged with the back of the disc A, to function in the manner described.

Fig. 3 shows a modified form of device, wherein the recessed portion or casing F¹ is made integral with the bracket G. In this instance, the reinforcing plate E¹ is provided with peripheral guide flanges E³, E⁴, slidably fitted within the recess F⁵, and is con-

fined in place by a bolt J⁵ extending through a plain opening in the rear wall of the recess and provided on its protruding end with suitable adjustable lock nuts J⁶. As the parts are thus modified, the wiping pad may be adjusted relatively to its support to make resilient contact with the mold disc simply by manipulating the nuts J⁶, which need only be set in position to permit the pad to be pressed forwardly by the spring H the necessary extent.

Having thus described my invention, its construction and mode of operation, what I desire to secure by Letters Patent of the United States is set forth in the following claims:

1. In or for a slug casting machine, a mold wiper comprising a support formed with a recess, a wiping pad movably mounted in the recess, a reinforcing plate attached to the wiping pad, a spring located in the support recess and acting to press the pad outwardly, and a confining screw cooperating with the reinforcing plate to limit the outward movement of the pad. 75

2. In or for a slug casting machine, a mold wiper comprising a support formed with a recess, a wiping pad movably mounted in the recess, a reinforcing plate attached to the wiping pad, a spring located in the support recess and acting to press the pad outwardly, a confining screw cooperating with the reinforcing plate to limit the outward movement of the pad, and a fixed bracket to which the support is adjustably connected. 85

3. In or for a slug casting machine, a mold wiper comprising a support formed with a cup-like recess, a wiping pad mounted in said recess, a reinforcing plate attached to the wiping pad, and a spring located in the recess and acting upon the reinforcing plate to render the wiping pad resilient. 95

4. In or for a slug casting machine, a mold wiper comprising a support formed with a cup-like recess, a wiping pad mounted in said recess, a reinforcing plate attached to the wiping pad, a spring located in the recess and acting upon the reinforcing plate to render the wiping pad resilient, and a guide pin projecting forwardly from the base of the recess and passing through a central opening in the reinforcing plate to guide the pad in its movements. 105

In testimony whereof, I have affixed my signature hereto.

ALBERT L. CHALFONTE.
